Primary Examiner—Holly H. Baynham*Assistant Examiner*—Cynthia M Chin*(74) Attorney, Agent, or Firm*—Seed IP Law Group PLLC**CLAIM**

The ornamental design for a offset turner handle, as shown and described.

DESCRIPTION

FIG. 1 is a rear, top perspective view of a offset turner handle showing a first embodiment of my new design.

FIG. 2 is a top plan view thereof.

FIG. 3 is a right side elevation view thereof.

FIG. 4 is a left side elevation view thereof.

FIG. 5 is a bottom plan view thereof.

FIG. 6 is a rear elevation view thereof.

FIG. 7 is front elevation view thereof.

FIG. 8 is a rear, top perspective view thereof shown in an alternate environment.

FIG. 9 is a rear, top perspective view thereof shown in another alternate environment.

FIG. 10 is a rear, top perspective view thereof shown in yet another alternate environment; and,

FIG. 11 is a rear, top perspective view of an alternate embodiment.

The broken lines in the figures are for illustrative purposes only and form no part of the claimed design.
